UNITED STATES PATENT OFFICE.

JOHN L. KELLY AND PATRICK L. McARDLE, OF CHICAGO, ILLINOIS.

GOLF-CLUB.

1,064,916.

Specification of Letters Patent. Patented June 17, 1913.

Application filed June 13, 1910. Serial No. 566,478.

To all whom it may concern:

Be it known that we, JOHN L. KELLY and PATRICK L. McARDLE, citizens of the United States, and residents of Chicago, in the 5 county of Cook and State of Illinois, have invented certain new and useful Improvements in Golf-Clubs; and we do hereby declare that the following is a full, clear, and exact description thereof, reference being 10 had to the accompanying drawings, and to the letters of reference marked thereon, which form a part of this specification.

This invention relates to an improvement in golf clubs and consists of the matters 15 hereinafter described and more particularly pointed out in the appended claims.

In the drawings:—Figure 1 is a front elevation of our improved golf club in position addressing the ball, showing part of the 20 shaft broken away. Fig. 2 is a vertical section through the head of the club in a vertical plane through the axis of the shaft. Fig. 3 is a section through Fig. 2 on the line 3—3 thereof.

25 A indicates the shaft or handle of the club and B the head. The head B is spheric in form with the center of the sphere located in line with the central axis of the shaft A. A segment of the sphere is cut away in front 30 as at b to form a bearing for a plate b¹ which provides the driving face of the club. Said face b is preferably made at an angle to a vertical plane. A segment of the sphere is also preferably removed at the base of the 35 head to provide a substantially flat rest b⁵ for the club when addressing the ball.

Our improved club, formed as illustrated and described, is particularly advantageous 40 for the reason that on account of its approximation to the shape of a sphere the center of gravity of the head lies in or near the plane containing the central axis of the shaft and the central point of the driving face, and but very little back of the prolongation 45 of the central axis of the shaft. The club approximates perfect balance, and in its operation nearly approaches the ideal theoretical club,—that is to say, a ball at the end of a string. The removal of the lower segment of the sphere forming the head to provide the horizontal base b⁵ brings the center of gravity of the head more nearly into a horizontal plane through the center of the ball and prevents “topping” the ball. Our 50 improved club may be used equally well as a wooden club or as an iron or as a putter.

In order to vary the angle of the face of the club, the face plate b¹ is attached to the head in such manner as to be removable as follows: The shaft A is provided with a reduced end part a having a screw-thread a¹ formed at the upper end of said reduced part. The reduced end part of the shaft engages within a radial socket B² formed in the head. The upper end of said socket 60 has an internal screw-thread B³ adapted to receive the thread a¹ on the shaft. The face piece b¹ is provided at its rear with a central stud b² which engages within a radial socket b³ extending transversely through the 65 head. A transverse-opening b⁴ is formed in the stub b² of the same diameter as and coaxial with the socket B² to receive the reduced end a of the shaft. It is thus apparent that the face b¹ is locked in place by the 70 engagement of the reduced end of the shaft within the transverse opening through the 75 stud b².

A number of face plates b¹ having their outer faces at different angles, as indicated by 80 the dotted lines b⁵, in Fig. 3, may be applied with each club so as to provide faces which may be used in place of the various wooden and iron clubs, such as driver, brassie, mashie, cleik or mid-iron. Our improved 85 club may thus be used as a universal club, several different face pieces being carried by the player, either of which may be readily attached when a particular play requires its use. 90

We claim as our invention:—

1. A golf club comprising a shaft and a spherical head, the center of the sphere being substantially co-incident with the central axis of the shaft and said sphere being 95 cut away on one side in a plane, a removable face piece parallel to said plane, a stud formed on the rear of said face piece, the head being provided with a socket to receive said stud, and means for removably 100 securing said shaft to the head and for interlocking the end of said shaft with said stud.

2. A golf club comprising a shaft provided with a thread near its end, a spherical 105 head, a radial socket in said head adapted to receive the end of said shaft, part of said socket being internally screw-threaded, the center of the sphere being substantially co-incident with the central axis of the shaft 110 and said sphere being cut away on one side in a plane, a removable face piece adapted 115

- to engage the plane side of said head, and a stud formed on the rear of said face piece, said head having a transverse socket to receive said stud, and said stud being interlocked with said shaft end.
3. A golf club comprising a shaft and a head, the center of the head being substantially in alignment with the central axis of the shaft, and said head being cut away on one side in a plane, a removable face piece parallel to said plane, a stud formed on the rear of said face piece, the head being pro-
- vided with a socket to receive said stud, and means for removably securing said shaft to the head and for interlocking the end of said shaft with said stud. 15
- In testimony, that we claim the foregoing as our invention we affix our signatures in the presence of two witnesses.
- JOHN L. KELLY.
PATRICK L. McARDLE.
